[57] CLAIM

The ornamental design for a jewelry display case, as shown and described.

DESCRIPTION

FIG. 1 is a perspective view of the jewelry display case according to the invention;

FIG. 2 is a front view thereof;

FIG. 3 is a rear view thereof;

FIG. 4 is a top view thereof;

FIG. 5 is a bottom view thereof; and,

FIG. 6 is a right side view thereof, the opposite side being a mirror image.

The broken line showing of knobs and hardware is for illustrative purposes only and forms no part of the claimed design.
